UNITED STATES PATENT OFFICE.

HERMANN A. SIEVERT, OF WALLA WALLA, WASHINGTON.

BRIDLE-BIT.

SPECIFICATION forming part of Letters Patent No. 773,429, dated October 25, 1904.

Application filed February 27, 1904. Serial No. 195,642. (No model.)

To all whom it may concern:

Be it known that I, HERMANN A. SIEVERT, a citizen of the United States, and a resident of Walla Walla, in the county of Walla Walla 5 and State of Washington, have invented a new and Improved Bridle-Bit, of which the following is a full, clear, and exact description.

This invention relates to bridle-bits; and it consists, substantially, in the construction and 10 combinations of parts hereinafter particularly described, and pointed out in the claims.

One of the principal objects of the invention is to provide a bridle-bit capable of being used as a curb-bit and a snaffle-bit, either 15 singly or combined, and also to overcome numerous disadvantages and inconveniences common to many forms of bridle-bits hitherto devised.

A further object is to provide a bridle-bit 20 of the character referred to which is simple in the construction and organization of parts constituting the same, besides being comparatively inexpensive to manufacture and possessing the capacity for long and repeated 25 service.

The above and additional objects are attained by means substantially such as are illustrated in the accompanying drawings, in which similar characters of reference indicate corresponding parts in all the figures.

Figure 1 is substantially a front elevation of my improved bridle-bit. Fig. 2 is a side view thereof. Fig. 3 is a view in elevation looking at the structure from the upper end 35 thereof. Fig. 4 is a transverse sectional view taken on the line 4-4 of Fig. 1. Fig. 5 is a view in perspective of the connecting-yoke employed between the lower ends of the branches or side pieces of the bit. Fig. 6 is 40 a plan view representing several different sizes of links which may be employed for uniting the inner ends of the snaffle-sections of the bit, and Fig. 7 is a detail view hereinafter more particularly described.

Before proceeding with a more detailed description it may be stated that in the form of my improvements herein shown I employ a curb-bit and a snaffle-bit of special construction and operation, the two being co-operatively 45 organized in such manner as to be capable of

being operated both together or singly, either as may be desired in the use of the structure. For the curb-bit I employ branches or side pieces of special construction at the upper end portions thereof for the attachment thereto of 55 the ends of the curb strap or chain and for other purposes hereinafter explained, the lower ends of said branches being connected or united by a yoke, also of special construction. For the snaffle-bit I employ snaffle-sections of special embodiment or form at the outer ends thereof for effecting the desired connection between such ends and the branches before mentioned, the said sections being provided with rings for the connection therewith of the usual reins and straps, while the yoke referred to is also provided with means for connection therewith of a third rein for 60 operating upon the curb-bit when desired.

I have herein represented my improvements 70 in a certain preferred embodiment; but it will be understood, of course, that I am not limited to the precise details thereof in practice, since immaterial changes therein may be resorted to coming within the scope of my invention. 75

Specific reference being had to the drawings by the designating characters marked thereon, 11 represent the branches or side pieces of the curb-bit structure, the same being practically duplicates and each being 80 formed at the upper end thereof with an enlargement 2, having therein an opening 3, in which is inserted and held a hook, ring, or other device 4 or 4^a, to which is secured an end of the curb strap or chain 5. (See Figs. 85 1, 2, and 3.) The lower ends of said branches or side pieces are connected by means of a yoke 7, constructed, preferably, of a single piece and having end portions 8 passing through openings therefor in said lower ends of the 90 branches, the longer parallel portions 9 of the yoke being contracted or brought together and secured substantially centrally of the length thereof, as indicated at 10, and carried by the yoke at this point is a ring 11, to which attachment may be made of one end of a third rein, (not shown,) which may be carried around in any suitable manner and attached to some part of the harness—say to the pom- 95 mel of a riding-saddle—to be taken hold of by 100

the operator for the purpose of applying the curb in the usual manner. The yoke 7 by its construction also serves to strengthen and brace the said lower ends of the branches or side pieces, as is apparent. As shown in Figs. 5 and 2, I may also attach to the lower portion of each branch or side piece substantially a D-shaped loop 12 for the purpose of using a double rein, (not shown,) if desired, in lieu 10 of the third rein referred to, it being understood that the term "third" has been employed to signify the use of another rein besides the habitual operating-reins (also not shown) for snaffle action, which are generally 15 fastened in the rings 16, to which also the check-pieces of the usual bridle are attached. The enlargements 2 of the branches or side pieces 1 are also formed with circular openings 12^a, in which are received and supported 20 in a universal manner the spherical heads 13, formed with or attached to the outer ends of the snaffle-sections 14 of the bit structure, the inner ends of these sections being preferably flattened and perforated, as shown, to receive 25 the hook portions of substantially an S-shaped connecting-link 15 therefor, the said sections being also provided near their outer ends with rings 16, to which attachment may be made of the usual operating-reins (not shown) 30 hereinbefore referred to. The openings 12^a of the branches or side pieces 1 are of slightly-greater diameter than the maximum diameter of said spherical heads 13 of the snaffle-sections, (see Fig. 7), and applied to the opposite sides of the enlargement 2 of each branch or side piece are flat disks 17, having 35 openings therein somewhat less in diameter than the said openings 12^a, the edges of said openings 17 being beveled inwardly, as shown 40 at 18. From this construction it will be seen that the curb-bit structure may be operated independently of the snaffle-bit structure, and vice versa, and also that the two said structures may be operated combinedly or at the 45 same time, if so desired. A minimum of friction results from the described spherical connection between the branches and the snaffle-sections, as is apparent, and the operation of the entire embodiment is most effective 50 and reliable.

Accordingly as it may be desired to lengthen or shorten the mouthpiece formed by the two snaffle-sections, a longer or shorter connecting-link 15 may be employed, and instead of 55 employing a curb-strap, as herein shown, I

may employ any suitable form of curb-chain, also as is apparent.

In the use of a combination-bit structure of the character herein set forth all injury to the jaws and tongue of a horse is avoided, since 60 the snaffle-sections will not rise in the mouth of the animal on operating the curb-bit structure, due to the universal connection between the branches and the said sections. Other advantages of the general embodiment will be 65 more apparent without further elucidation, although it may be added that my improved combination bit is intended more especially for use when riding in the saddle.

Having thus described my invention, I claim 70 as new and desire to secure by Letters Patent—

1. A bridle-bit comprising a snaffle structure and a curb structure, and ball-and-socket connectors between said structures.

2. A bridle-bit comprising a snaffle structure and a curb structure, a ball carried at each end of the snaffle structure, and coacting 75 sockets carried by the curb structure.

3. A bridle-bit comprising side branches, a yoke connecting the lower ends thereof, constructed of parallel members brought together 80 at their central portions, and a ring held by said portions.

4. A bridle-bit comprising a snaffle structure, side branches having universal connection therewith, a curb connecting the upper ends of the branches, and a yoke connecting the lower ends thereof, said yoke being constructed of parallel members brought together 85 at their central portions and provided at such 90 portions with a ring.

5. A bridle-bit comprising spherical heads at the ends thereof, side branches having openings in their upper end portions in which said heads are partially received, said openings being of greater diameters than the maximum diameters of the heads, and disks on either side of each of said end portions, having openings in which the heads are also partially received, said latter openings being less in diameter than the maximum diameters of said heads, and having the edges thereof beveled. 95 100

In testimony whereof I have signed my name to this specification in the presence of two subscribing witnesses.

HERMANN A. SIEVERT.
